UNITED STATES PATENT OFFICE.

CHARLES H. R. GODFREY, OF SOUTH NORWALK, CONNECTICUT.

LABEL-LOCK.

SPECIFICATION forming part of Letters Patent No. 576,571, dated February 9, 1897.

Application filed April 23, 1896. Serial No. 588,705. (No model.)

To all whom it may concern:

Be it known that I, CHARLES H. R. GODFREY, a citizen of the United States, residing at South Norwalk, in the county of Fairfield 5 and State of Connecticut, have invented certain new and useful Improvements in Label-Locks; and I do hereby declare the following to be a full, clear, and exact description of the invention, such as will enable others skilled 10 in the art to which it appertains to make and use the same.

My invention has for its object to provide a label-lock adapted for general use, as, for example, upon mail-bags or freight-cars, 15 which shall be simple and inexpensive to produce, strong and durable, and thoroughly practical in use.

With these ends in view I have devised the novel label-lock, of which the following 20 description, in connection with the accompanying drawings, is a specification, numbers being used to designate the several parts.

Figure 1 is a plan view illustrating the application of my novel lock to a mail-bag strap; 25 Fig. 2, a section on the line $x-x$ in Fig. 1; Fig. 3, a view corresponding with Fig. 1, except that the locking-block is removed; Fig. 4, a similar view showing the application of my invention to a hasp-lock, and Fig. 5 is a 30 view showing the cap-plate of the locking-block removed and illustrating a simple form of locking mechanism.

1 denotes the label-holder, which is provided with a longitudinal slot 2 to receive a strap 3. This slot may extend entirely 35 through the label-holder, as clearly shown in Fig. 2, as when the lock is used in connection with a leather strap, or the label-holder may be made integral with a hasp 4, as when the 40 lock is used upon a car-door or any analogous use, the strap in this instance being preferably of metal.

5 denotes the label, which may be made of paper, metal, or any suitable substance, and 45 which is adapted to slide into a socket 6 in the label-holder.

7 denotes the locking-block, which just fits a recess 8 at one end of the label-holder. Within the locking-block I place suitable 50 locking mechanism, which, however, specif-

ically forms no portion of my present invention.

In Fig. 5 I have shown a simple form of locking mechanism consisting, essentially, of spring-actuated tumblers, which are adapted 55 to engage locking-recesses 10 in a stud 11, which extend upward from the bottom of the label-holder and in recess 8. When a leather strap is used, as in locking a mail-bag, the strap is passed through slot 2, as clearly shown 60 in Fig. 2, stud 11 being passed through one of the holes in the strap to retain the lock in position thereon. A buckle may or may not be used, as shown in Fig. 1.

Having passed the strap one or more times 65 around the bag or other articles to be locked, the strap may be retained in the tightened position by the buckle, and then the end of the strap passed into slot 2 and stud 11 passed through one of the holes near the end 70 of the strap, as is clearly shown in Fig. 2, the end of the strap lying above the other portion of the strap. After the label has been slipped into the socket the bag is locked, and the label also locked in the socket by 75 placing locking-block 7 in recesses 8 and causing stud 11 to pass through an opening 12 in the under side of the locking-block, tumblers 9 being forced back to allow the head 13 of the stud to pass and then engaging 80 the locking-recesses after the head has passed to retain the locking-block in the locked position. The operation is the same when the label-holder is made integral with a hasp, as shown in Fig. 5. In this form the 85 strap may or may not be made of metal and is provided with a hole through which stud 11 passes in approximately the same manner as before. The outer side of the locking-block is provided with a keyhole 14, through 90 which a key is passed to actuate the tumblers against the power of their springs to release stud 11. As soon as the tumblers have been disengaged from the locking-recesses in the stud the locking-block may be removed from 95 the label-holder. The end of the strap may then be removed from the recess and the bag, car-door, or other article upon which the lock is used may be opened and the label may be removed from its socket. To lock the 100

strap in position, the key is not required, it being simply necessary to place the locking-block over the stud, the latter registering with opening 12, and press the locking-block 5 to place in recess 8.

It should be noted that the locking-blocks are made interchangeable, it being intended when the lock is used upon mail-bags that the locking mechanism in a number of locking-blocks be made to be controlled by a single key in precisely the same manner that ordinary mail-bag locks are controlled, that is to say, the locking mechanism of all the locking-blocks are controlled by one key and 15 every person whose business it is to open mail-bags is provided with a key and also, if required, with extra locking-blocks. In locking up a mail-bag, therefore, it is simply necessary to take any locking-block and place 20 it in position on any label-holder.

Having thus described my invention, I claim—

1. A label-lock consisting of a label-holder provided with a socket to receive a label, a 25 longitudinal slot to receive a strap, a recess,

a stud extending upward from the bottom of the label-holder in slot 2 and a bodily-detachable locking-block which is adapted to engage the recess and obstruct the label-passage and is provided with locking mechanism which 30 engages the stud.

2. A label-lock consisting of a label-holder provided with a socket to receive a label, a longitudinal slot to receive a strap, a recess, a stud extending upward from the bottom of 35 the label-holder in slot 2 and provided with locking-recesses 10, a bodily-detachable locking-block which is adapted to engage the recess in the holder and obstruct the label-passage and is provided with locking mechanism 40 and an opening in its under side which receives the stud, the locking mechanism engaging the locking-recesses in the stud.

In testimony whereof I affix my signature in presence of two witnesses.

CHARLES H. R. GODFREY.
